BRUSH HOLDER

Loren D. Britton, Hinsdale, Ill., assignor to General Motors Corporation, Detroit, Mich., a corporation of Delaware

Application September 2, 1944, Serial No. 552,451

4 Claims. (Cl. 171—324)

1

This invention relates to new and useful improvements in electrical brush holders.

The principal object of the present invention is to provide a simple, rugged brush holder assembly including adjustable brush tensioning means in which a spring is included whereby a brush may be supported and tensioned in proper manner and so that the spring may be rendered inoperative to tension the brush and then serve to hold a part of the tensioning means in a retracted position in order to facilitate inspection and replacement of the brush.

The form and arrangement of the elements comprising the brush holder assembly by which this object is accomplished and other novel features thereof will become apparent by reference to the following detailed description of and accompanying drawing illustrating the invention.

Figure 1 of the drawing is a transverse cross sectional elevation view of the brush holder.

Figure 2 is a partial plan view of the brush holder with the end portions broken away and

Figure 3 is a partial end elevation view of the brush holder with the end and other portions broken away to show certain details of the elements to better advantage.

The brush holder assembly comprises a body member 1, preferably formed by casting, having a supporting boss 3 on one end provided with conventional insulated mounting studs, not shown, for attachment to the stator of a dynamoelectric machine adjacent the commutator or a slip ring 5 of the machine rotor, shown in dotted lines in Figure 1. The body 1 is provided with a terminal boss 7 on the other end having tapped holes 9 for binding posts, not shown, by which the main brush current conductor, not shown, is connected thereto. A plurality of brush slots 11 with a depression 13 alongside of each slot are spaced longitudinally between the ends of the body 1 and a tubular shaft 15 is secured in aligned openings in vertical transverse webs 17 of the body between each of the depressions 13.

Identical brush tensioning means comprising a fork-shaped brush finger 19, a brush spring 21 and a spring tension adjusting lever 23 are rotatably supported on the shaft in each of the body depressions 13. The two legs of the forked inner end of each brush finger 19 are provided with aligned openings through which the shaft 15 extends and the outer end of each finger is provided with an arcuate tip, shown in contact with the outer end of a brush 25 in Figure 1. An upstanding boss or finger grip 27 is provided on each finger to aid in retracting the finger from

2

the brush. A flexible electrical conductor 29 is secured to the inner end of each finger and each of these conductors are electrically connected by a separate binding post 31 threaded into the brush holder body 1. Each brush 25 has a flexible pigtail conductor 33 secured thereto and each of these conductors is connected to a separate binding post 34 threaded in the body 1. Each brush spring 21 comprises two helical coil portions axially spaced apart on the shaft 15 between the legs of each brush finger, a central connecting loop portion adapted to bear on the outer end of the finger and upstanding end portions. A spring adjusting lever 23 is pivoted at its inner end on the shaft 15 between the two helical coil portions of each spring 21 and a grooved anchor pin 35 is secured to the outer end of the lever for connecting the upstanding ends of a spring 21 so that the spring exerts an angular separating force between a lever and a finger. In order to anchor the spring adjusting levers 23 in different angular positions on the body to vary the spring force applied to the brush fingers 19 an arcuate portion 37 having angularly spaced notches 39 is provided on the inner end of each lever, the arcuate portion 37 being concentric to the shaft 15 and locking keys 41 are movably mounted on the body 1 adjacent each of the levers by means of locking studs 43. Each of these keys are movable into engagement in any slot in the lever adjacent thereto and is clamped to the body by a separate locking stud 43. Each of the above described levers and lever locking means provide convenient means for adjustment of the tension of each of the brush springs. The keys 41 also serve as a stop to limit the retracting movement of the brush fingers 19 as each of these fingers are provided with a boss 44 which contacts one of the keys.

It will be noted that the flexible conductors 29 and 33 electrically connect each brush and finger to the brush holder casting and it has been found that by use of a tube of Micarta or other insulating material for the tubular shaft 15 and bronze brush fingers 19 free movement of the fingers relative to the tube is obtained as there is no leakage current therebetween and no wear of the tube or finger due to current leakage.

The two helical portions of each spring 21 are wound so that each portion is supported on the Micarta tube 15 and is placed under compression between one side of a lever 23 and one leg of a finger 19 and accordingly one end coil of each helical spring portion frictionally engages one side of a lever 23 and the other end coil friction-

ally engages one leg of a finger 19. With a lever 23 locked to the brush holder body 1 by means of a key 41 extending into one notch of the arcuate portion 37 of a lever 23, when the upstanding ends of the spring 21 are disengaged from the opposite ends of the lever anchor pin 35 the outer end of an adjacent finger 19 may be easily moved away from the brush 25 by means of the finger grip 27 and the finger 19 will be held in the fully retracted position with the finger boss 44 in contact with the key 41 by the frictional engagement exerted by the end coils of the spring 21 on the lever 23 and on the finger 19.

This feature enables the brushes to be readily removed for inspection or change in the confined spaces in which the brush holders are usually positioned. It will be evident that when the upstanding ends of a spring 21 are engaged with the opposite ends of a lever anchor pin the helical portions of a spring will be wound up and the central portion of the spring will engage the outer adjacent end of a finger and resiliently urge the arcuate outer end portion of the finger into contact with a brush 25 and hold the inner surface thereof in contact with the commutator 5. The force exerted by the spring 21 on a brush 25 may be varied by inserting the locking key 41 into the different notches in the arcuate portion 37 of the lever 23.

I claim:

1. A brush holder comprising a body having a brush slot extending therethrough, a brush finger and lever movably mounted on the body, means for locking the lever in different positions with respect to the body and resilient means between and in frictional engagement with the finger and lever to frictionally hold the finger in different positions with respect to the brush slot and lever, said resilient means having portions adapted to be engaged with the lever and finger to urge the finger toward the brush slot and away from the lever.

2. A brush holder comprising a body having a brush slot extending therethrough, a brush finger and lever pivotally mounted on said body, means for locking said lever in different angular positions with respect to said body and a spring between and in frictional engagement with the finger and lever for frictionally holding the finger in different angular positions with respect to the lever and brush slot, said spring having portions adapted to be engaged with said lever and finger to cause said finger to be urged toward said slot and away from said lever.

3. A brush holder comprising a body having a

brush slot extending therethrough and means located adjacent said slot for attaching a flexible brush conductor, a brush finger, spring, and spring adjusting lever supported for rotation on said body adjacent said slot, a flexible conductor connected between said finger and said body, said finger having an arcuate outer end portion movable into said brush slot and a forked inner end portion extending on opposite sides of said lever, means for locking said lever in different angular positions on said body, said spring having portions frictionally engaging the forked end of said finger and said adjusting lever to hold the outer arcuate end of said finger in a retracted position relative to said slot and portions adapted to be engaged with said finger and said lever to cause said spring to exert variable separating force between said finger and said adjusting lever depending upon the position of said lever to cause the outer arcuate end of said finger to be moved into said brush slot.

4. A brush holder comprising a body having a brush slot extending therethrough and means located adjacent said slot for attaching a brush conductor, an insulating shaft secured to said body adjacent said slot, a lever rotatably supported on said shaft, means for locking said lever in different angular positions with respect to said body, a brush finger having a forked end, the two legs of which are rotatably supported on said shaft either side of said lever and the other end of said finger having an arcuate tip adapted to enter the brush slot, a flexible conductor connected between said finger and body and a spring having two helical portions each supported on said shaft between the lever and one leg of the forked end of said finger and in frictional engagement with said finger and lever, a central portion engageable with the finger and end portions adapted to be connected with said lever to apply angular separating force between said lever and finger to urge the arcuate end of said finger toward the brush slot.
